United States Patent Office

Des. 219,997
Patented Feb. 23, 1971

219,997

DEPTHMETER

Alfons Z. Rachwalski, Miraleste, Calif. (6520 Madeline Cove Drive, Palos Verdes Peninsula, Calif. 90274)

Filed Oct. 14, 1969, Ser. No. 19,549

Term of patent 14 years

Int. Cl. D10—07

U.S. Cl. D52—6

Fig. 1

Fig. 2

Fig. 3

Fig. 4

FIG. 1 is a front elevation of a depthmeter showing my new design;

FIG. 2 is a side elevation thereof;

FIG. 3 is a rear elevation thereof; and

FIG. 4 is a bottom plan view thereof.

The broken lines are shown for illustrative purposes and forms no part of the claimed design.

I claim:

The ornamental design for a depthmeter, as shown and described.
